A. G. REDMOND

FUEL FEEDING SYSTEM FOR MOTOR VEHICLES

Filed Oct. 31, 1923

UNITED STATES PATENT OFFICE.

ALBERT G. REDMOND, OF INDIANAPOLIS, INDIANA, ASSIGNOR TO JACOB RICHARD FRANCIS, OF FLINT, MICHIGAN.

FUEL-FEEDING SYSTEM FOR MOTOR VEHICLES.

Application filed October 31, 1923. Serial No. 671,906.

This invention relates to fuel feeding systems for motor vehicles, the object being to provide means in the form of an electric pump for pumping fuel from a low level 5 fuel tank to a supplemental reservoir from which the fuel is fed to the charge forming device by gravity.

Another and further object of the invention is to provide an electric pump with a 10 valve controlled outlet actuated by a float within the supplemental reservoir so that when the fuel rises to a predetermined level within the supplemental reservoir, the outlet will be closed so as to stop the operation 15 of the pump in order to maintain a predetermined level of fuel within the supplemental reservoir at all times.

A still further object of the invention is to provide a fuel feeding system in which 20 an electric pump is employed having a movably mounted piston which is raised by a solenoid and allowed to drop by gravity so that fuel will be displaced from the cylinder of the pump.

Other and further objects and advantages 25 of the invention will be hereinafter set forth and the novel features thereof defined by the appended claims.

In the drawings,

Figure 1 is a diagrammatic view showing 30 the wiring and arrangement of the fuel feeding system; and

Figure 2 is a vertical section through the supplemental tank and pump showing the 35 interrupter in elevation and the charge forming device partly in section.

In carrying out my invention I employ a supplemental reservoir 1 which can be arranged in any desired position on the motor 40 vehicle in a plane above the carburetor and I preferably arrange the reservoir under the hood of the motor vehicle to which the system is applied.

The reservoir 1 is provided with an outlet 45 2 having a feed pipe 3 connected thereto extending to the inlet bowl 4 of the carburetor 5 so that fuel within the supplemental reservoir 1 will flow by gravity to the carburetor.

Arranged within the reservoir 1 is an electric pump comprising a base 6 having a cylinder 7 surrounded at its upper end by a solenoid 8 which is grounded as shown at

9 and is arranged within an electric circuit having a source of electrical energy in the form of a battery 10 which is grounded as 55 shown at 11.

Extending from the battery to the upper end of the solenoid is a feed wire 12 having an interrupter 13 provided with a fixed contact 14 and a movable contact 15 for making 60 and breaking the circuit for energizing and de-energizing the solenoid. The movable contact is actuated by a cam 16 driven by any of the movable parts of the motor to which the system is applied so that the 65 solenoid will be energized and de-energized as the motor operates and while I have not shown any connection with the motor, the form of interrupter as herein shown and its connection to the motor is illustrated in an 70 application filed even date herewith.

The base 6 of the pump extends through the bottom of the supplemental reservoir 1 and is provided with an inlet 17 to which is connected a pipe 18 extending from the main 75 fuel supply tank 19 arranged in a plane below the carburetor and from which fuel is adapted to be drawn by the pump into the supplemental reservoir.

Arranged within the pump cylinder is a 80 piston 20 forming the core of the solenoid and which is adapted to be raised when the solenoid is energized and allowed to drop by gravity when the solenoid is de-energized. The down stroke of the piston is 85 arrested by a spring 21 as clearly shown.

The base is provided with an inlet check valve 22 and an outlet check valve 23 which are herein shown of the sliding type of valve now in use in connection with pumps. 90 The base is also provided with an outlet nipple 24 having a vertical pipe secured therein which extends upwardly into the supplemental reservoir 1 and has a head 26 secured on its upper end provided with outlets 27 which are adapted to be closed by a valve 28 having a stem 29 carrying a float 30.

As the fuel is pumped from the low level reservoir into the supplemental reservoir, it 100 passes out from the outlets 27 and the capacity of the pump is such that the supply from the main reservoir to the supplemental reservoir is in excess of the consumption of

fuel by the charge forming device so that fuel always remains within the supplemental reservoir and when the level of the fuel therein rises above a predetermined point, 5 the float 30 rises and cuts off the outlet of the pump to the receptacle 1. This stops the movement of the piston of the pump until the level drops so as to open the outlet as the particular construction of pump here-
 10 in shown is such that the stroke of the piston is such that when the piston is raised by the solenoid being energized it rides on the fuel in the cylinder of the pump and if the fuel is held therein the piston is not al-
 15 lowed to drop. If it drops slightly when the solenoid is again energized, it will move slightly, but I have found in practice that after the outlet of the pump has been cut off by the rising of the fuel in the supple-
 20 mental reservoir and the solenoid has been energized and de-energized once or twice, the piston will remain inactive until the fuel level in the supplemental reservoir drops to such an extent that the outlet valve is
 25 opened.

The supplemental reservoir is provided with a cover having a vent, which cover is preferably made removable so that the pump can be inserted and while I have shown cer-
 30 tain details of construction, I do not wish to limit myself to these details, as the object of my invention is to provide an auxiliary reservoir arranged in a plane above a carbureter having a pump disposed therein pro-
 35 vided with a valve controlled outlet actuated by a float so that when the fuel within the auxiliary reservoir reaches a predetermined level, the outlet valve will be closed and by the use of a particular construction of pump
 40 as herein shown and manner of operating the same, the pump will cease to operate until the fuel drops below the predetermined level.

While in the drawings I have shown the outlet of the pump having a stand pipe con-
 45 nected thereto, it is, of course, understood that I am aware that the outlet could be pro-
 vided with a check valve to which is con-
 nected a float so as to accomplish the desired result.

50 From the foregoing description it will be seen that I have provided a fuel feeding system for motor vehicles in which fuel is pumped from a low level tank to a high level tank having a float for cutting off the supply
 55 of fuel to the high level tank when the fuel therein reaches a predetermined level whereby I am able to maintain a reservoir of fuel for the charge forming device within the supplemental tank at all times so that an
 60 ample supply of fuel will be supplied to the charge forming device at all times and under all conditions.

While in the drawing I have shown the pump arranged within the receptacle to
 65 form a single unit, it is, of course, under-

stood that the receptacle can be separate and distinct from the pump as by arranging the pump outside of the receptacle and having the inlet extending into the receptacle and providing the top of the pump with an over-
 70 flow for the leakage, the device will operate in the same way. Therefore, I do not wish to limit myself in a fuel feeding system to the use of a pump within the receptacle.

I am also aware that various other changes in the details of construction can be made without departing from the spirit of my in-
 75 vention.

What I claim is:—

1. In a fuel feeding system for motor ve-
 hicles, the combination with a low level fuel
 tank, an auxiliary tank arranged in a plane
 above said auxiliary reservoir, a carbureter
 supplied with fuel from said auxiliary reser-
 80 voir by gravity, a pump arranged in said
 auxiliary reservoir having inlet and outlet
 check valves and an outlet port, a valve con-
 trolling said outlet port, a float mounted in
 said reservoir connected to said valve, said
 85 pump consisting of a pump barrel, a solenoid
 and piston in the form of a core and means
 for energizing and de-energizing said sole-
 noid.

2. In a fuel feeding system for motor ve-
 hicles, the combination with a main fuel
 supply tank, of a carbureter located in a
 plane above said tank, an auxiliary reser-
 90 voir feeding fuel to said carbureter by
 gravity, a pump arranged within said auxil-
 iary reservoir for pumping fuel from said
 tank to said reservoir, said pump comprising
 95 a pump chamber and a piston movably
 mounted therein, a source of current and an
 electric circuit including a solenoid for actuating
 said piston, means timed by the engine
 100 for energizing and de-energizing said sole-
 noid and a float actuated valve for control-
 ling the outlet of said pump.

3. In a fuel feeding system for motor
 vehicles, the combination with a main fuel
 supply tank, of a carbureter arranged in a
 plane above said tank, an auxiliary reser-
 110 voir arranged in a plane above said carbureter,
 a pump for pumping fuel from said
 main tank to said auxiliary reservoir, said
 pump having a valve controlled outlet, a
 115 float mounted in said auxiliary reservoir
 for actuating said valve, said pump com-
 prising a pump chamber and a piston mov-
 ably mounted therein, a source of current, an
 120 electric circuit including a solenoid for rais-
 ing said piston and means timed by the
 engine for energizing and de-energizing
 said solenoid.

4. A fuel feeding system for motor ve-
 hicles comprising a main fuel supply tank,
 an auxiliary tank and a carbureter fed by
 gravity from said auxiliary tank, a pump
 arranged in said auxiliary tank having a
 125 slidably mounted piston, said pump being

provided with a valve controlled outlet, a float mounted in said tank connected to said valve, a source of electrical energy, an electric circuit including a solenoid for actuating the piston of said pump, an interrupter arranged in said circuit, and means actuated by the engine for operating said interrupter.

5. A fuel feeding system for motor vehicles comprising a main fuel supply tank and an auxiliary tank for supplying fuel to the carbureter by gravity, a pump arranged in said auxiliary tank having a slidably mounted piston, a pipe connected to the outlet of said pump carrying a valve casing, a valve mounted in said casing for closing the outlet thereof, a float connected to the stem of said valve and adapted to raise said valve when the fuel within said auxiliary tank reaches a predetermined level, a source of 20 electrical energy, an electric circuit including a solenoid for actuating the piston of said pump and means timed by the engine

for energizing and de-energizing said solenoid.

6. In a fuel feeding system for motor vehicles, the combination with a carbureter, of a main fuel supply tank arranged below said carbureter, an auxiliary tank arranged above said carbureter and adapted to feed fuel thereto by gravity, a pump arranged 25 within said auxiliary reservoir having a slidably mounted piston, a solenoid for raising said piston, a source of current, an electric circuit including a solenoid, means for making and breaking said electric circuit for 30 energizing and de-energizing said solenoid, a stand pipe connected to the outlet of said pump, a valve for controlling the outlet of said stand pipe and a float for actuating 35 said valve.

In testimony whereof I hereunto affix my signature.

ALBERT G. REDMOND.
